UNITED STATES PATENT OFFICE.

ANNA M. THOMPSON, OF NEW YORK, N. Y.

GARMENT HANGER.

Application filed July 26, 1922. Serial No. 577,627.

To all whom it may concern:

Be it known that I, ANNA M. THOMPSON, a citizen of the United States, and a resident of the city of New York, borough of 5 Manhattan, in the county and State of New York, have invented new and useful Improvements in Garment Hangers, of which the following is a full, clear, and exact description.

10 This invention relates to garment hangers.

A garment hanger which is adapted for carrying the whole suit is very convenient and satisfactory. Consequently many efforts have been made to provide a simple garment 15 hanger which has more than one supporting means so that a complete suit may be carried by the one hanger and arranged so that either garment may be removed from or replaced upon the hanger without the inconvenience of removing the other.

The general object of this invention is the provision of a simple and efficient garment hanger provided with more than one garment supporting unit, and so constructed 25 that a garment may be removed from one of the garment supporting members without disturbing the garments carried by the other garment supporting member.

A further object of the invention is the 30 simplification of garment hanger construction by providing a garment hanger formed from one piece of wire.

These objects are accomplished by so bending 35 one piece of wire so as to form on one end of the wire means for attaching it to hooks and the like, and, on the lower end of a standing member depending from the hook, a curved garment support, and forming about the standing member at a point above 40 the curved garment support a second garment support consisting of two jaws that may be operated to grip a garment.

These and other objects of the invention will be more clearly understood from the following detailed description and accompanying drawings, in which—

Figure 1 is a perspective view of the garment hanger;

Figure 2 is a top plan view of the garment support formed on the standing member;

Figure 3 is a section along the line 3—3, Figure 2;

Figure 4 is a detailed view showing how the garment support shown in Figure 2 is 55 attached to the standing member.

Referring to the above-mentioned draw-

ings, a single length of wire is bent to form a hook 10 on one end. This hook serves as a means for attaching the garment hanger to a hook or any other support that would be 60 provided. Depending from the hook 10 is a standing member 11. On the lower end of the standing member 11 a curved garment support 12 is formed by first bending the wire into the left of the standing member 65 11, then bending it back upon itself, and extending it to the right of the standing member, from whence it is bent back upon itself and brought to the standing member. The wire is then wound about the standing member as shown at 13. The garment support 70 12 formed on the lower end of the standing member is curved and extends equally on both sides of the standing member 11. After the wire has been twisted about the standing 75 member 11 it is bent to the left and then doubled back upon itself to the standing member, forming a loop 15, when it is projected through a loop 14 formed in the standing member. The wire is now carried 80 to the right a distance equal to the length of the loop 15 formed on the left of the standing member 11 forming an arm member 19. The wire is again bent back on its 85 self, forming a jaw 16 which is equal in length to the loop 15 and the arm 19 extending to the right of the standing member 11. At 17 the jaw 16 is bent slightly so as to space the jaw 16 from the loop 15. The end of the jaw 16 is bent downward forming a 90 projection 18 which may be engaged in the loop 15. Thus it will be seen that two jaws are formed, one being the jaw 16 while the other includes the loop 15 and the arm 19. The jaws are held together by means of the 95 projection 18 which engages in the loop 15, thus serving to support any garment such as a pair of trousers or a shirt. The garment support 12 serves to support the coat and vest of a suit or the coat of a lady's suit. 100

From the above it will be evident that a simple garment hanger has been devised which is so constructed from one piece of wire that more than one garment supporting member is provided. These garment supporting members are so arranged that a garment may be removed from or placed on either of the garment supporting members without disturbing the garment or garments carried by the other. Such a construction 105 is of great value and convenience to the user.

I would state in conclusion that while the

illustrated example constitutes a practical embodiment of my invention I do not limit myself strictly to the exact details herein illustrated since manifestly the same can be considerably varied without departing from the spirit of the invention as defined in the appended claim. 20

Claim:

A garment hanger formed from a single length of wire comprising a hook formed at the upper end thereof, said wire then extending downward to provide a standing member, said member provided with a loop, the lower end of the standing member formed into a curved garment support by doubling the wire back upon itself defining two arms extending on opposite sides of the standing member, a second garment support formed on the standing member above the first named garment support, said second garment support formed by bringing the wire back along the standing member from the lower garment support, folding it to form an arm at one side of the standing member, said arm presenting an eye at its outer end, then carrying the wire through the aforesaid loop in the standing member and forming a U-shaped arm on the opposite side of the standing member, carrying the wire across said standing member parallel to the arm presenting the eye, and forming a hook at its end for engagement with said eye. 25 30
